UNITED STATES PATENT OFFICE.

MICHAEL RUCKES, OF CHICOPEE FALLS, MASSACHUSETTS, ASSIGNOR TO NATIONAL SCALE COMPANY, OF CHICOPEE FALLS, MASSACHUSETTS, A CORPORATION.

DESIGN FOR A SCALE-FRAME.

41,304.

Specification for Design.

Patented Apr. 11, 1911.

Application filed December 20, 1910. Serial No. 598,473. Term of patent 14 years.

To all whom it may concern:

Be it known that I, MICHAEL RUCKES, a citizen of the United States of America, residing at Chicopee Falls, in the county of Hampden and State of Massachusetts, have invented a new, original, and ornamental Design for Scale-Frames, of which the following is a specification, reference being had to the accompanying drawing, forming part thereof.

The figure is a perspective view of a scale frame showing my new design.

I claim:

The ornamental design for a scale frame as shown.

MICHAEL RUCKES.

Witnesses:

K. I. CLEMONS,
HARRY W. BOWEN.

Copies of this design may be obtained for five cents each, by addressing the "Commissioner of Patents, Washington, D. C."
